(57) **CLAIM**

The ornamental design for a handle for dental tool, as shown and described.

DESCRIPTION

FIG. 1 is a front elevational view of a handle for dental tool showing my new design;

FIG. 2 is a top view thereof;

FIG. 3 is a bottom view thereof;

FIG. 4 is a left end view thereof; and,

FIG. 5 is a right end view thereof.

The rear elevational view is a mirror image of the front elevational view illustrated in FIG. 1 and the brush tips illustrated in dashed lines do not form part of the claimed design.
